(57) **CLAIM**

The ornamental design for a light fixture cover, as shown and described.

DESCRIPTION

FIG. 1 is a top perspective view of our new design of the light fixture cover;

FIG. 2 is a bottom perspective view of the light fixture cover;

FIG. 3 is a top view of the light fixture cover;

FIG. 4 is a bottom view of the light fixture cover;

FIG. 5 is a right side elevational view of the light fixture, the left side being a mirror image; and,

FIG. 6 is a front view of the light fixture cover, the rear view being a mirror image.

The area between the curved lines which indicate that the cover is shown broken away forms no part of the claimed design.
